UNITED STATES PATENT OFFICE.

BERNARD M. O'BOYLAN, OF CORNING, OHIO.

CANDLE-HOLDER.

SPECIFICATION forming part of Letters Patent No. 338,099, dated March 16, 1886.

Application filed August 10, 1885. Serial No. 174,019. (No model.)

To all whom it may concern:

Be it known that I, BERNARD M. O'BOYLAN, a citizen of the United States, residing at Corning, in the county of Perry and State of Ohio, have invented new and useful Improvements in Candle Holders and Adjusters, of which the following is a specification.

My invention relates to an improved candle-holder and guard-plate for detachable connection to socketed candlesticks, by which means are provided for supporting candles of various diameters, and also for catching the drip.

The invention consists of a concaved metal dish or guard-plate having a pair of elastic concaved fingers attached centrally to its upper surface, and a pair of spring-catches secured to its under side, said fingers and catches being held securely in place by means of a nut and a spur-pointed screw, the latter serving also as a point of attachment for the candle and to prevent any liability of displacement.

In the annexed drawings, illustrating my invention, Figure 1 is a view of my improved candle-holder and guard-plate. Fig. 2 is a sectional elevation of the same attached to a candlestick.

Referring to the drawings, the numeral 1 designates a slightly-concaved metal disk or dish, which serves as a guard-plate or drip-cup for catching drip from the candle as it is consumed. To the upper surface of this guard-plate is attached a pair of concaved elastic fingers, 2, which consist of a metallic strip of proper width, having its opposite ends bent up at right angles to the central portion, 3, of said strip. The upward-bent ends that constitute the elastic fingers 2 are concaved longitudinally, as shown, to conform to the cylindrical shape of the candle, and, being formed of spring metal, are sufficiently elastic to grasp candles of various diameters. The elastic fingers 2 are secured to the guard-plate 1 by a screw-bolt, 4, passed through the central portion, 3, of the metallic strip from which said fingers are formed. This screw-bolt also serves to secure to the under side of the guard-plate a pair of spring-catches, 5, which are made in a manner similar to the elastic fingers 2—that is, from a strip of spring metal, with ends turned at a right angle to the central portion of the strip and concaved. The metallic

strip from which the spring-catches are formed may, however, be of less width and length than that from which the elastic fingers are made. It will be observed that the elastic fingers 2 are braced by the connecting portion 3 of the strip from which they are formed, said connecting portion serving as a base from which the elasticity of the fingers is exerted. This is also true of the spring-catches 5 and 6, their connecting-base 6. The connecting screw-bolt 4 is passed up through the center of the guard-plate 1, and through the respective bases 3 and 6 of the elastic fingers 2 and spring-catches 5, and is secured by a nut, 7, on the upper side of the guard-plate. It will be observed that the screw 4 projects somewhat above the connecting-base of the elastic fingers, and, being provided with a sharpened end or spur, serves as a point of attachment for the lower end of the candle, which can be pressed down thereon, thus obviating any liability of accidental displacement.

The spring-catches 5 are made of any required length or conformation to fit candlestick-sockets of various sizes.

When the device is in position upon a candlestick, a candle of any ordinary thickness can be readily inserted within the elastic fingers 2, and upon the upward-projecting ends of the screw 4, and as it is consumed, or when reduced greatly in length, the candle can be raised within the elastic fingers until held by their upper ends only. By this means, therefore, a candle can be readily consumed to its end, while the guard-plate protects the candlestick or any object on which it may be placed from drip and grease.

It will be observed that when a tall candle is inserted in the holder it can be pressed down until its lower end is pierced by the sharp-pointed screw-bolt 4, which thus serves to steady the candle and prevent toppling. After the candle has been partly consumed the shortened end can be detached from the screw-point 4 and be adjusted vertically to any required height, or until it is held by the elastic fingers 2 alone.

What I claim as my invention is—

1. The combination, in a candle-holder, of a guard-plate, elastic fingers bent up from a single metallic strip and having a connecting-

base, by which they are attached to the upper surface of said guard-plate, spring-catches, also bent from a single metallic strip, with a connecting-base by which they are attached to the under side of said guard-plate, and a screw-bolt and nut for connecting the guard-plate, fingers, and catches, substantially as described.

2. The combination, in a candle-holder, of the concaved guard-plate 1, the concaved elas-

tic fingers 2, having an integral connecting-base, 3, the spring-catches 5, also having an integral base, 6, the spur-pointed screw-bolt 4, and the nut 7, substantially as described.

In testimony whereof I affix my signature in presence of two witnesses.

BERNARD M. O'BOYLAN.
